UNITED STATES PATENT OFFICE.

STEPHEN AUGUSTUS HASBROUCK, OF NEW YORK, N. Y.

CONVERTIBLE COMPOUND EXPLOSIVE-ENGINE.

SPECIFICATION forming part of Letters Patent No. 624,649, dated May 9, 1899.

Application filed February 17, 1898. Serial No. 670,696. (No model.)

To all whom it may concern:

Be it known that I, STEPHEN AUGUSTUS HASBROUCK, a citizen of the United States, residing in the city of New York, in the county of New York and State of New York, have invented certain new and useful Improvements in Gas, Oil, and other Like Engines, which are fully set forth in the following specification.

10 My invention relates to the arrangement and operation of the valves in gas, oil, and other like engines having both high and low pressure cylinders; and its object is to provide a simple and speedy means of transforming 15 a compound engine to a double or "twin" engine, and vice versa.

The most important feature of my invention is the addition of an auxiliary valve operating in connection with the usual valves, as 20 hereinafter set forth, and the mechanism for so operating the valves herein described will also be claimed as a separate feature.

My invention also involves the addition of an igniter to the low-pressure cylinder.

25 My invention is of especial utility in gas, oil, or other like engines used for traction purposes, where it is of great importance for the operator to have an additional source of power to be used when needed on account of 30 heavy grades, rough roads, or other impediments, and to be able to bring such extra power into use speedily and by simple means. My invention enables the operator to do this by the transformation mentioned, which greatly 35 increases the power of the engine for the time being. When the extra power is no longer needed, the engine can be instantly brought back to its ordinary mode of operation.

The accompanying drawings illustrate so 40 much of the mechanism as is necessary to an understanding of my invention.

Figure 1 shows the valves and connecting-passage in section and the remainder of the mechanism, including the mechanism for operating the valves, in perspective. Fig. 2 shows simply a section of the valves and connecting-passage.

The several parts of the mechanism are designated as follows in the drawings and in the 50 references thereto.

A and B are the cylinders, A being used as

the high-pressure cylinder and B as the low-pressure cylinder when the engine is operated as a compound engine.

I indicate the igniters for each cylinder. 55 More than one high-pressure cylinder may be used in exactly the same manner, if desired.

D is the admission-valve, and C the exhaust valve, of the cylinder A. F is the admission-valve, and E the exhaust-valve, of 60 the cylinder B. The admission-valves are each connected with the reservoir in which the gas or other medium is stored by a common supply-pipe. This is not shown in the drawings, as it is simply the usual construction. The exhaust-valves C and E open into and are connected by a passage H, containing an auxiliary valve G, opening on the outer air, with or without a "muffler" to deaden 65 the sound. The valves may be of any of the usual and approved forms. In the drawings they are supposed to be of the ordinary "pop" variety. The mechanism for their operation is illustrated in the drawings, Fig. 1, as follows:

75 The valves D and C are operated by a slide 7, which is attached by means of the links 6 6 to a bell-crank lever 5, which is journaled on a shaft 2. The valves F and E are operated by a similar slide 21, which is attached by 80 the links 14 14, the pin 12, and the links 15 15 to a lever 16 on a shaft 3, turned by a crank 22. The slide 21 has an extension 19, which engages with another lever 17, fastened to the shaft 3. There is also another bell-crank 85 lever 11 on shaft 2, having at the end of its upper arm a slot 13, adapted to engage with the pin 12.

The two bell-crank levers 5 and 11 and the lever 9 are actuated, respectively, by cams 4, 90 8, and 10 on a cam-shaft 1. The lever 17 is provided with a shoulder 27, which engages with the shoulder 26 of lever 16. Another shoulder 28 of lever 17 engages with the shoulder 29 of catch 18. 20 and 23 are springs operating as hereinafter set forth. When not actuated by the mechanism described, the valves are held in their seats by springs. The auxiliary valve G is operated by a lever 9, 95 journaled on the shaft 2 and having a toe 30, adapted to engage with the catch 18, journaled on shaft 3. The cam-shaft 1 is actuated by

100

the crank-shaft 25 by means of the usual gearing 24. The several shafts are set in the engine in the usual manner, which it is not deemed necessary to represent.

5 The method of operation of the mechanism is as follows, taking for the purposes of the description a gas-engine of the usual type, with one high-pressure and one low-pressure cylinder: The drawings represent the machine in operation as a compound engine. The cam-shaft 1, actuated by the crank-shaft of the engine, which is started in the usual manner, revolves in the direction indicated by the arrow at one-half the speed of the 15 crank-shaft, and the cam 4, engaging with the bell-crank lever 5, pulls down the slide 7 by means of the links 6 6, and thereby pushes down the stem of the admission-valve D, thus opening it and admitting the charge into the 20 cylinder A. After the "toe" of the cam has passed the bell-crank lever 5 the slide 7 is brought back by the spring to its "neutral" position, thus closing the valve D. The same result may also be accomplished independently of the spring by using a cam provided with two toes of proper shape. The charge thus admitted is compressed and ignited in the usual manner and by its expansion furnishes the power-stroke of the high-pressure 25 cylinder. At the end of the stroke the cam 4 pushes up the slide 7 by means of the bell-crank lever 5 and the links 6 6, thus opening the exhaust-valve C. The gas thus allowed to escape passes through the passage H and 30 into the cylinder B through the valve E, held permanently open by the lever 17, supporting the extension 19 of the slide 21. The lever 17 is fastened by a set-screw or other convenient means on the shaft 3, which is operated 35 by the crank 22 and locked in the desired position by a catch on the crank. The gas, being thus admitted to the cylinder B, expands further and produces the power-stroke of that cylinder, the igniter thereof not being used 40 when the engine is working compound. At the end of this stroke the cam 8 (also driven by the cam-shaft 1) lifts the lever 9, and thus pushes open the valve G, so that the charge is exhausted into a muffler or into the outer 45 air. The valve G thus acts as the exhaust-valve for the cylinder B. While the engine is operated in this manner, the admission-valve F of cylinder B is held shut by its spring. The pin 12 is held out of engagement with the 50 bell-crank lever 11 by the links 15 15 and the lever 16, which is locked in its required position by the shoulder 27 engaging with the shoulder 26. The catch 18 is held out of engagement with lever 9 by the shoulder 28 engaging with its shoulder 29.

When it is desired to change from a compound engine to a twin, this is done as follows: The operator unlocks the crank 22 and revolves it, as shown by the arrow. This 55 lowers the lever 17 and allows the extension 19 and the slide 21 to descend and the valve E to be closed by its spring. At the same

time the catch 18, being thus released, is lowered by the action of its spring 23 and comes into engagement with the toe 30 of lever 9 as such lever is lifted by the cam 8. The spring 23 holds the catch 18 in this position, and the lever 9, with which it is engaged, thus holds the valve G permanently open. Meanwhile the same revolution of the crank 22 releases 75 the lever 16, and the spring 20 pulls the pin 12 into engagement with the slot 13 at the end of the upper arm of the bell-crank lever 11, where it is held in such engagement by said spring. The slide 21 is thus brought into connection by means of the links 14 14 with the bell-crank lever 11 and is actuated by the cam 10 in a manner similar to that described for the slide 7, bell-crank lever 5, and cam 4. (It is to be observed that when the engine is run 80 as a "compound" the cam 10 simply rocks the bell-crank lever 11 without further transmitting its motion.) The crank 22 is then revolved still further to remove all danger of the shoulders 26 and 27 striking as the lever 85 16 oscillates. With the mechanism in the condition described each cylinder acts as a high-pressure cylinder and is operated in the same manner as that first described for the cylinder A, so that the engine becomes a twin 90 high-pressure engine, and the auxiliary valve G being held permanently open the passage H becomes practically a part of the atmosphere. In this mode of operation the igniter 95 for the low-pressure cylinder is used. To 100 change back to a compound engine, the above operation is simply reversed and need not be described in detail. The crank 22 is revolved in the opposite direction, the shoulders 27 and 28 engage with the shoulders 26 and 29, respectively, the pin 12 is released from the slot 13, thus disconnecting the slide 21 from the bell-crank lever 11, the lever 17 comes in contact with the extension 19 and raises the slide 105 21, the catch 18 is disengaged from the lever 110 9 and the valve G thus released, and the engine thus returns to the condition first described.

What I claim as new, and desire to secure by Letters Patent, is as follows:

1. In a gas, oil or other like engine, the combination of a plurality of cylinders having igniters, independent admission-valves and independent exhaust-valves for each cylinder, a passage connecting the exhaust-valves of two cylinders, a valve in said passage opening to the atmosphere, with means operable to set the exhaust-valve of one of said cylinders open and the corresponding admission-valve closed, and means operable to open and close the valve in said passage, whereby the engine may be operated as a multiple-cylinder high-pressure or as a compound engine, substantially as described.

2. In a gas, oil or other like engine, the combination of a plurality of cylinders, independent admission and exhaust valves for each cylinder, a passage connecting the exhaust-valves and having a port leading to the at-

mosphere, a normally open auxiliary valve for closing said port, operating devices for the admission and exhaust valves of each cylinder, and means throwing said devices for one of said cylinders out of action and permitting the closure of said auxiliary valve, substantially as described.

In testimony whereof I have signed this specification in the presence of two subscribing witnesses.

STEPHEN AUGUSTUS HASBROUCK.
